UNITED STATES PATENT OFFICE.

ZIVA POPIN, OF NEW YORK, N. Y.

HAIR-CURLING DEVICE.

Application filed May 17, 1919, Serial No. 297,765. Renewed July 20, 1922. Serial No. 576,355.

To all whom it may concern:

Be it known that I, ZIVA POPIN, residing at New York, in the county and State of New York, have invented certain new and 5 useful Improvements in a Hair-Curling Device, of which the following is a specification.

This invention relates to hair curling devices, and one of the objects of the invention 10 is to provide a new and improved curler, which is intended primarily for use with apparatus designed to produce what is known as a permanent curl or wave in hair upon the head.

15 Another object of the invention is to provide a device of the above character upon which the hair may be easily and conveniently wound, and which will hold the hair thereon in a tightly wound condition.

20 Other objects and aims of the invention, more or less specific than those referred to above, will be in part obvious and in part pointed out in the course of the following description of the elements, combinations, arrangements of parts and applications of 25 principles, constituting the invention; and the scope of protection contemplated will be indicated in the appended claims.

In the accompanying drawing, wherein I 30 have illustrated a preferred form of embodiment of my invention:

Figure 1 is an elevational view of my improved device.

Figure 2 is a similar view, showing the 35 parts in open position; and

Figure 3 is a sectional view taken on line 3—3 of Figure 1.

Before proceeding to describe the structural features of my invention, it may here 40 be noted that the device which forms the subject matter of this application is designed primarily for use in what is known as "Marcel waving." Heretofore this waving has been accomplished by means of the ordinary form of heater curling iron, which, while satisfactory in so far as the quality 45 of the wave produced is concerned, does not operate to impart to the hair a wave having the characteristics of what is known as the permanent wave, that is to say, a wave which 50 will stand shampooing and will last for an indefinite period. By the use of my device, however, I am able to impart to the hair a Marcel wave to be practically permanent, in 55 a convenient and facile manner.

Referring now to the drawing, wherein

similar reference characters refer to similar parts through the several views thereof, the reference numeral 1 denotes the curler proper, the same comprising a circular rod 60 preferably bent in the form shown, so that it will conform to the shape of the head, that is to say, the concave side will lie in close engagement with the part of the head in which is located the hair to be treated. The 65 concave part 2 of the curler is provided with a groove 3, which is adapted to receive a clamping rod 4, which is pivoted as at 5 to one end of the curler 2. This rod when in normal position lies in the groove 3, as 70 clearly shown in Figures 1 and 3.

Pivoted upon the opposite end of the curler 2, at 6, is a holding member 7, having a hook-shaped outer end 8 which is adapted to embrace the end of the curler 2, to which 75 the clamping rod 4 is attached, as clearly shown in Figure 1. It will be noted that both the clamping member 4 and the holding member 7 are curved to conform to the curvature of the curler 2.

In the use of my device the end of a selected lock or tuft of hair is caught between the clamping member 4 and the curler 2, the clamping member 4, of course, being closed upon the end of the tuft or lock so as 85 to clamp it between itself and the curler 2, the holding member 7 being of course moved to an open position. The device is then rotated to roll the hair about the curler 2 of the clamping member 4. That is to say, the 90 device is rotated by the fingers of the operator so that the entire lock or tuft of hair is wound about the curler beginning with the outer end and extending inwardly toward the scalp. The holding member 8 is then 95 moved to the position shown in Figure 3, thereby clamping the coiled hair and preventing the hair from becoming unwound from the curler. If desired, metallic points 9 may be provided upon the holding member 100 7, which aid in the maintaining of the hair upon the curler.

It will accordingly be seen that I have provided a construction well adapted to attain, among others, all the aims and objects 105 pointed out, in an exceedingly simple yet efficient manner.

As many changes could be made in this construction without departing from the scope of the following claims, it is intended 110 that all matter contained in the above description or shown in the accompanying

drawing shall be interpreted as illustrative only and not in a limiting sense.

Having thus described my invention what I claim as new and desire to secure by Letters Patent is:

1. A device of the class described, comprising a curler formed of a curved rod, a clamping member pivoted to one end thereof, a holding member pivoted to the other end thereof, said clamping and said holding members conforming to the shape of the curler, and said holding member being provided with a hook-shaped end for engaging the end of the curler opposite its pivotal mounting.
2. A device of the class described, comprising a curler formed of a curved rod having a clamping member pivoted to one end thereof, said clamping member being adapted to engage the ends of a lock or tuft of hair and hold it between itself and the curler, so that said lock or tuft may be coiled upon both of said elements, and a holding member pivoted to the opposite end of said curler adapted to engage the coiled hair having a hook-shaped end adapted to engage the end of said rod opposite its point of pivotal connection.

3. A device of the class described, comprising a curler formed of a curved rod having a recess in its concaved side, a clamping member pivoted to one end of said curler adapted to lie in said recess, a holding member pivoted to the opposite end of said rod, and having means for engaging the end of the curler opposite to which it is pivoted, whereby the hair upon the curler may be fixedly held in position.

4. A device of the class described, comprising a curler formed of a curved rod having a recess in its concaved side, a clamping member pivoted to one end of said curler adapted to lie in said recess, a holding member pivoted to the opposite end of said rod, having means for engaging the end of the curler opposite to which it is pivoted, whereby the hair upon the curler may be fixedly held in position, and said holding member being provided with a plurality of points adapted to engage the hair.

In testimony whereof I affix my signature in the presence of two witnesses.

ZIVA POPIN.
